CLAIM

The ornamental design for a corner lip shroud, as shown and described.

DESCRIPTION

FIG. 1 is a perspective view of a first embodiment of a corner lip shroud showing my new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a bottom view thereof;

FIG. 7 is a rear elevational view thereof;

FIG. 8 is a view taken along elevational line 8—8 of FIG. 5;

FIG. 9 is a view taken along elevational line 9—9 of FIG. 7; and,

FIG. 10 is a perspective view of a second embodiment thereof being a mirror image of FIG. 1 with all other views being a mirror image of FIGS. 2—9.
